UNITED STATES PATENT OFFICE.

HARRY L. BALDWIN, OF WASHINGTON, DISTRICT OF COLUMBIA.

ELECTRIC-LIGHTING GAS-BURNER.

No. 908,538.

Specification of Letters Patent.

Patented Jan. 5, 1909.

Application filed June 1, 1908. Serial No. 436,088.

To all whom it may concern:

Be it known that I, HARRY L. BALDWIN, citizen of the United States, residing at Washington, in the District of Columbia, have invented certain new and useful Improvements in Electric-Lighting Gas-Burners, of which the following is a specification.

The present invention provides novel 10 gas lighting means for hand operated gas burners of the type equipped with spark producing means actuated by the act of turning on the gas.

The objects sought are to prevent waste of 15 electric energy; to minimize wear on the electrodes and gas valve; to reduce the cost of maintenance to the smallest amount possible; to devise effective, durable and simple 20 gas lighting means readily adaptable to any hand operated gas burner and positive, cer- 25 tain and reliable in operation, and to supply a burner of the type aforesaid which will not be liable to hang and which is easily operable both when turning on or shutting 30 off the gas, the spark being produced when the gas is turned on and the electrodes clearing each other when the gas is turned off.

For a full understanding of the invention 35 and the merits thereof and also to acquire a knowledge of the details of construction 40 and the means for effecting the result, reference is to be had to the following description and accompanying drawings.

While the invention may be adapted to 45 different forms and conditions by changes in the structure and minor details without departing from the spirit or essential features thereof, still the preferred embodiment is shown in the accompanying drawings, in which:

Figure 1 is a perspective view of a hand 50 operated gas lighting burner embodying the invention. Fig. 2 is a side view thereof, the full lines showing the normal position of the parts when the gas is shut off and the dotted lines showing the position of the parts when the gas is turned on and the spark about to be produced. Fig. 3 is a front view. Fig. 4 is a perspective view of a modification. Fig. 5 is a view similar to Fig. 3 of a further modification.

Corresponding and like parts are referred 55 to in the following description and indicated in all the views of the drawings by the same reference characters.

The burner 1 may be of any make or de-

sign and is provided with the usual tip and the accustomed valve or gas cock 2 for regulating the flow of gas. A lever 3 is provided for operating the valve or gas cock 60 2 and may have direct connection with the latter, as indicated in Figs. 1 and 5, or may be mounted upon a stud 4, as shown in Figs. 2 and 3, said stud projecting from the body of the burner and the lever 3 having connection with the valve or gas cock 2 so as to oscillate the same. As indicated in Figs. 2 and 3 a pin 5 projects outward from the gas valve 2 and is arranged eccentric thereto and enters a slot 6 provided in the lower 65 portion of the lever 3. Any suitable means may be provided to limit the movements of the lever 3, such as a stop 7 which may consist of a pin projected outward from the burner and adapted to operate in a cut away 70 portion of the lever 3. A cross head 8 is provided at the upper end of the lever 3 and terminates at its ends in wings 9 which support an arm 10. An electrode 11 is mounted upon the arm 10 and moves therewith into 75 and out of the way of an electrode 12 at- 80 tached to the burner 1 near its tip and elec- 85 trically insulated therefrom. The arm 10 may be mounted either to rock, as shown in Figs. 1, 2, 3 and 4, or to oscillate, as indi- 85 cated in Fig. 5.

In the preferred construction, the arm 10 is mounted to receive a rocking movement, the projecting end being out of axial alignment, whereby upon the application of 90 force to move the lever 3, the arm is rocked either to throw the electrode 11 into or out of the way of the electrode 12 according as the gas is to be turned on or off. An end portion of the arm 10 projects beyond the 95 cross head and is formed with an off-set 13 which throws the outer end of said arm out of line with the inner end. The off-set portion 13 operates between a pair of pins 14 which are so positioned as to limit the rock- 100 ing movements of the arm. An operating wire 15 is loosely connected with the outer end of the arm 10 and serves to rock the latter both when said wire is pulled upon to turn on the gas, or pushed upon to turn the 105 gas off. When pulling upon the wire 15 the arm 10 is moved to throw the electrode 11 into the way of the electrode 12, and upon pushing upon the wire 15 the arm 10 is moved to throw the electrode 11 out of the 110 way of the electrode 12. A spring may be arranged to coöperate with the arm 10 to in-

sure positive movement thereof and to overcome the weight of the operating wire 15. As indicated in Fig. 2, the spring 16 is of the coil type and mounted upon the arm 10, 5 one end of said spring operating against the cross head 8 and its opposite end upon the arm 10. As indicated in Fig. 4, a flat-spring 17 is connected at one end to the lever 3 and its opposite end co-operates with 10 a tongue 18 projected from the arm 10. A spring 19 of the coil type has one end connected with the burner and its opposite end attached to a pin 20 projected from the arm 10. The spring 19 is of the contractile type 15 and is arranged to hold the lever 3 in either of its two extreme positions and also to carry said lever to the end of its movement in either direction after clearing the dead point.

20 In the construction shown in Fig. 5, the arm 10 is mounted at one end in a wing 9 of the cross head 8 and its opposite end portion passes through an inclined slot 21 formed in the opposite wing. In this construction, the arm 10 receives an oscillatory movement in contradistinction to the rocking movement of the arm as mounted in the remaining figures. When pulling upon the operating wire 15, the projecting end of the 25 arm 10 is moved downward and inward by the action of the inclined slot 21, thereby bringing the electrode 11 into the way of the electrode 12, as shown most clearly by the dotted lines in Fig. 5. Upon pushing upward upon the wire 15, the outer end of the arm 10 is carried upward in the inclined slot 21, thereby moving the electrode 11 outward so as to clear the electrode 12 upon the 30 movement of the lever 3 to turn off the gas.

35 40 The remaining parts are arranged substantially in the manner set forth in connection with Figs. 1, 2 and 3.

When the gas is turned off, the lever 3 and co-operating parts occupy the relative 45 positions shown in Figs. 1 and 2, (the full lines in the latter figure), and when the gas is turned on the parts occupy the position substantially as indicated by the dotted lines in Fig. 2. The initial pull upon the wire 15 50 either rocks or oscillates the arm 10 to move the same to bring the electrode 11 into the way of the electrode 12. A continued pull upon the wire 15 moves the arm 3 to both turn on the gas and to bring the electrodes 55 11 and 12 into and out of contact so as to produce the spark for lighting the gas at the burner tip. To turn off the gas an upward push upon the wire 15 insures movement of the arm 10 to carry the electrode 11 60 out of the way of the electrode 12 and to rock the lever 3 to operate the gas valve or cock 2 so as to turn off the gas. It is to be understood that the spring provided to co-operate with the arm 10 may move the latter at 65 the end of the movement of the lever 3 after

the gas has been turned on and lighted, so as to throw the electrode 11 out of the way of the electrode 12. When the spring so acts, the upward movement of the wire 15 serves simply to move the lever 3 to turn off the gas, as will be readily understood.

In the construction shown in Fig. 4 the spring 17 performs substantially the same office as the part 10, *i. e.*, it acts as an arm to carry the movable electrode 11. When 75 the arm 10 is rocked in one direction the tongue 18 is withdrawn from the part 17 which by its resiliency springs inward to bring the electrode into position to engage with the electrode 12. A movement of the 80 arm 10 in the opposite direction brings the tongue 18 in contact with the spring arm 17 and moves its end outward to carry the electrode 11 out of the way of the electrode 12 upon the return of the lever 3 to normal 85 position.

Having thus described the invention, what is claimed as new is:

1. In an electric lighting gas burner comprising a gas valve and a fixed electrode, a 90 lever arranged for actuating said gas valve to turn on or off the gas, said lever having a cross head provided with wings, an arm mounted in said wings and adapted to receive a movement and having an end portion 95 extended beyond the cross head, a movable electrode carried by said arm, and operating means applied directly to the outer end of said arm to move the latter upon the initial application of force to 100 throw the movable electrode into or out of the way of the fixed electrode and to move said lever to turn the gas on or off.

2. In an electric lighting gas burner comprising a gas valve and a fixed electrode, a 105 lever arranged for actuating said gas valve to turn on or off the gas, said lever having a cross head provided with wings, an arm mounted in said wings and adapted to have movement imparted thereto, a movable electrode carried by said arm, operating means 110 having direct connection with the said movable arm, and a spring co-operating with said lever to insure movement of the same to the limit of its throw after passing the dead 115 point.

3. In an electric lighting gas burner comprising a gas valve and a fixed electrode, a lever arranged for actuating said gas valve to turn on or off the gas, said lever having a cross head provided with wings, an arm mounted in said wings to receive a rocking movement and having an end portion extended beyond the cross head and forming with an off-set spaced pins carried by said 120 cross head and co-operating with the off-set portion of said arm to limit its rocking movements, a movable electrode mounted upon said arm, and operating means applied directly to the projecting end of said arm 125 130

to rock the latter to move the lever to turn on or off the gas.

4. In an electric lighting gas burner, comprising a gas valve and a fixed electrode, a lever mounted upon the body of the burner and having an eccentric connection with the gas valve, an arm mounted upon the lever and having a movement independent thereof and provided with a movable electrode, and operating means for the lever having direct connection with said arm to move the same to throw the movable electrode into the way of the fixed electrode and to turn on the gas.

5. In an electric lighting gas burner, comprising a gas valve and a fixed electrode, a lever mounted upon the body of the burner and having eccentric connection with said gas valve, a cross head at the outer end of

said lever and provided with wings, an arm mounted in said wings and adapted to receive a movement independent of the lever, said arm having an end portion projected beyond the cross head, a movable electrode mounted upon said arm, a spring coöperating with the lever to insure movement of the same and the limit of its throw in each direction, and operating means applied directly to the projecting end of the aforesaid arm to effect movement both of said arm and lever.

20

In testimony whereof I affix my signature in presence of two witnesses.

HARRY L. BALDWIN. [L. s.]
